UNITED STATES PATENT OFFICE

151,403

DESIGN FOR A LINK CHAIN FOR A NECK-
LACE OR SIMILAR ARTICLE

Max Rahthus, New York, N. Y.

Application February 1, 1947, Serial No. 136,613

Term of patent 14 years

(Cl. D45—16)

To all whom it may concern:

Be it known that I, Max Rahthus, a citizen of the United States, residing in New York city, in the county of New York and State of New York, have invented a new, original, and ornamental Design for a Link Chain for a Necklace or Similar Article, of which the following is a specification, reference being had to the accompanying drawing, forming part thereof.

Fig. 1 is a fragmentary front elevational view of a portion of a link chain for a necklace or similar article.

Fig. 2 is a fragmentary side elevational view of the link chain; and

Fig. 3 is an end view taken from left of Fig. 2.

I claim:

The ornamental design for a link chain for a necklace or similar article, substantially as shown.

MAX RAHTHUS.
